UNITED STATES PATENT OFFICE.

LEE P. HYNES, OF ALBANY, NEW YORK, ASSIGNOR TO HYNES & COX ELECTRIC CORPORATION, OF ALBANY, NEW YORK, A CORPORATION OF NEW YORK.

ELECTRICALLY-HEATED TEMPERING BATH.

Application filed August 6, 1926. Serial No. 127,645.

For a detailed description of the present form of my invention, reference may be had to the following specification and to the accompanying drawings forming a part 50 thereof, wherein

Fig. 1 is a longitudinal section of my device on the line 1—1 of Fig. 2;

Fig. 2 is a plan view with the cover removed;

10 Fig. 3 is a diametric section of the heater with the coil in elevation taken on the lines 3—3 of Fig. 4;

Fig. 4 is a plan view of Fig. 3 with the cover removed.

15 My invention relates fundamentally to a method of heating electrically a liquid, such as the oil bath used for the tempering and heat treatment of many forms of metallic articles, wherein it is desired to maintain the 60 oil at a given temperature and in a clean condition. Heretofore it has been the practice to heat the oil electrically by placing in the body of oil an ordinary heater-coil suitably insulated and protected. The defect of 20 this method is that for a considerable body of oil a high temperature in the heater-coil is employed, the surface area of the coil being relatively small and intensely hot; hence the oil will often carbonize on the 65 surface of the heater and in time cause the heater to burn out because of inadequate radiation, while the oil becomes blackened and damaged by overheating. Also the oil near the heater is much hotter than that 30 farther away because the convection currents in the oil are very slow. For such operations as the drawing of steel tempered tools 70 uniformity of temperature in all parts of the oil bath is essential. Yet such uniformity of 35 temperature is not attainable in said prior arrangement, not only because of the unequal distance of different parts of the oil from the electric heater, but also because of the 80 local chilling of the oil by the cold steel when 40 first immersed. Nor is it possible to eliminate 85 this spotty heating by mechanically stirring the body of oil, as is also attempted in the prior art because of the imperfect convection of heat by the oil. I have suc- 90 45 100 105

cessfully overcome these troubles by the method of constantly drawing off the oil from the bath, forcing it in a stream through a coiled pipe which is electrically heated and then returning it to the bath. Preferably 50 the coil is separate from the bath so that no 110

part of the oil will receive extra heat by contact with the outside surface of the coil in distinction from the normal heat which every part of the oil receives from the interior surface of the coil in its journey there- 60 through. Moreover, the forced flow through the coiled pipe, which is a pipe of circular cross section, produces a swirling action of the oil that keeps all parts thereof constantly and thoroughly intermingled. 65 Thereby uniformity of temperature is promoted by the mutual convection of the intermingled parts, as well as by their uniform exposure to the heating agency. I have also devised other features that will be described 70 hereinafter.

Referring to the drawing, A represents a tank which, in this case, is rectangular in form and provided with double walls that enclose between them the heat-insulating 75 material B. A longitudinal L-shaped partition C divides the interior space into two compartments of which the larger one, of L-shaped contour, may be termed the inflow compartment and the smaller one, of plain 80 rectangular shape, the outflow compartment. Near the bottom of the latter is a horizontal screen D; while in the former, also near the bottom is a slow-moving conveyor belt E which is kept in constant motion by any 85 suitable external motive power, as is indicated by the crank-handle F. The oil enters by the upright inflow pipe G which passes down into the inflow compartment to a header G² from which two branch pipes g, 90 g extends out horizontally underneath the upper course of the conveyor belt E. The header G² and the branch pipes g, g, which constitute a distributor for the incoming oil, are perforated with holes at intervals 95 through which the oil enters the inflow compartment in distributed jets. These jets are more numerous at and near the header because it is at that end of the compartment that the cold articles to be treated are introduced. For example, the articles may be placed in a wire basket H, shown in Fig. 1, and lowered into the oil, through an up- 100 lifted lid I on the top of the tank, and there placed on the left-hand end of the conveyor belt. The belt carries them slowly through the oil to the right-hand end of the compartment, where the basket with its con- 105 tents is lifted out through an overlying cover-opening having a lid J. The basket 110

is then placed on said lid J which has a back-stop that keeps it in an inclined position when open. The oil drained from the cage flows down the inclined lid and back to the tank. In the top edge of the aforesaid partition C is a shallow notch C², about an inch in depth, through which the oil from the inflow compartment overflows into the outflow compartment, there falling down on the aforesaid screen D which removes from it any foreign matter. After passing through screen D to the bottom of the compartment, the oil is sucked up by the outflow pipe K, through the agency of pump P and delivered to the electric heater. The vertical tube T in the inflow compartment is open at both ends for the reception of a thermometer equipped to serve as a thermostat.

The heater is shown in Figs. 3 and 4. It has a cylindrical casing, with double walls enclosing heat insulation B², and a removable cover O. Within this casing a central metal frame M, carries on its outer periphery a series of vertical heater elements R, R, such, for example, as are shown in my Patent No. 1,549,773, granted August 18, 1925. Surrounding these and inside the annular space within the casing wall is a pipe-coil L through which the oil is circulated by pump P. As is indicated by dotted lines, the intake of the pump is connected with the outflow pipe K of the oil-tank, while the inflow pipe G of the tank draws from the outflow terminal of the coil M. The coil being located in the annular space between the heater elements R and the casing wall will be subjected throughout its entire helical length to the radially radiated heat of any desired intensity, said heat being distributed by the heater over the entire annular space, but the oil will not become carbonized because of its rapid flow in the pipe, while the heating effect of the heater elements will be limited by a thermostat in the box S at the outflow end of the pipe-coil where it is subjected to the temperature of the outgoing oil. An instrument-box Q on the outside wall of the casing contains the electrical control-switches, meters and connection-terminals. I have not shown herein the thermostat and the electrical details, nor the driving motor for the pump, since these may be of any suitable known construction (I have, however, shown in a separate application for patent a desirable system of electrical control for this oil tank and other tanks of a similar type). I call particular attention to the fact that the heating of the oil is carried on outside of and independently of the body of oil in the tank. Thus the utilization of the heated oil in the tempering or treatment of the metal articles is not affected by the changes and variations in temperature incident to the opera-

tion of securing and maintaining the oil temperature and keeping it constant and uniform. The latter operation is a separate and independent one, carried on by its own peculiar means in a way to adequately prepare the oil for its subsequent tempering or analogous function in the bath.

While I am claiming herein the above described apparatus and method for heating oil, it is to be regarded as only a specific embodiment of a more fundamental method of heating liquids, such as oils, syrups, and chemicals, that are liable to damage by a momentary or local excess of temperature. Thus it is difficult, if not impossible, to avoid in ordinary flame heaters, but can be avoided with certainty by my method, while, in addition, the whole body of liquid is raised to its desired maximum temperature at the maximum rate because the heating is applied to succeeding quotas of the mass within a region that is heated uniformly throughout by radiated electrical heat. The volume of the quota in a given time is dependent on the controlled velocity of flow. For illustration, my method has been adopted by the De Laval Separator Company to pre-heat transformer oil before clarifying it by centrifugal separators. Such oil is susceptible to carbonization which it is vitally important to avoid because it impairs its electrical insulating quality. In that operation the critical ratio between the three factors of heat energy, unit surface area, and unit volume per time unit, is found to be 1000 gallons of oil per hour, a heater coil of one and one-quarter inch outside diameter and nine watts per square inch of heating surface. In like manner the critical conditions for any similar liquid may be determined and maintained with speed and certainty. The volume that is at each moment subjected to the heating effect can be determined with accuracy and the heating effect can be controlled with equal accuracy. Moreover, the perfect mingling creates a mass of uniform temperature under certain and exact control.

What I claim as new and desire to secure by Letters Patent is:

1. A tempering apparatus for the treatment of metallic articles comprising a heat-insulated receptacle for containing a tempering liquid, a second heat-insulated receptacle, a liquid heating coil within the second receptacle, means also within the last mentioned receptacle for heating said coil by radiated electrical heat, and means for circulating said tempering liquid through said coil and also through the first mentioned receptacle consecutively so as to prevent a substantial drop in temperature of said liquid.

2. A tempering apparatus for the treatment of metallic articles comprising a heat-insulated receptacle having an inflow compartment and an outflow compartment,

- means by which liquid in the inflow compartment is caused to overflow into said outflow compartment, means within the inflow compartment for supporting the articles to be tempered, a heating coil, a conduit extending from the heating coil to the inflow compartment, a second conduit extending from the outflow compartment to said coil, and means for positively impelling said liquid.
- 5 3. A tempering apparatus for the treatment of metallic articles comprising a heat-insulated receptacle for containing a tempering liquid, a second heat-insulated receptacle, a liquid heating coil within the 10 second receptacle, means also within the last mentioned receptacle for heating said coil, an endless conveyor so positioned in the first mentioned receptacle that it will be submerged by said tempering liquid, a supply 15 conduit extending from said heating coil and having its discharge end located in the space enclosed by said conveyor, means for supplying tempering liquid to said coil from the first mentioned receptacle, and means for 20 positively impelling said liquid.
4. A tempering apparatus for the treatment of metallic articles comprising a heat-insulated receptacle provided with an inflow compartment and an outflow compartment 25 divided by an overflow partition, an endless conveyor located in the inflow compartment so as to support the articles to be tempered, a heating coil, a conduit leading from said heating coil and discharging in the space 30 enclosed by said conveyor, a second conduit 35 leading from the outflow compartment to said
- heating coil, and means for positively impelling said liquid.
5. A tempering bath for metallic articles or a similiar liquid body comprising a heat-insulated receptacle having two separate compartments communicating respectively with the inflow and outflow pipes from an electrically heated container, and a screen 40 in one compartment across the route of the heating medium leading to the outflow pipe from the bath.
6. A tempering bath for metallic articles or a similiar liquid body comprising a heat-insulated receptacle, inflow and outflow pipes 45 for said receptacle communicating with an electrically-heated container for the liquid, a screen interposed between said pipes so that the said medium will flow therethrough, and means for maintaining a circulation of 50 the liquid through the heater and the bath consecutively.
7. A liquid-heating apparatus comprising a receptacle for the liquid and a separate heater receptacle, means within the first mentioned receptacle for moving articles through said liquid, a pipe-coil in the heater-receptacle connected with said liquid receptacle, a series of distributed electric heating elements for distributing the heat over the 55 external surface of the coil and means for maintaining a flow of the liquid through said coil.

Signed at Albany, county of Albany,
State of New York, this 2nd day of Aug., 70
1926.
